UNITED STATES PATENT OFFICE.

WARREN S. SMITH, OF BANGOR, PENNSYLVANIA.

SIGNAL.

Application filed May 20, 1925. Serial No. 31,668.

To all whom it may concern:

Be it known that I, WARREN S. SMITH, a citizen of the United States, residing at Bangor, in the county of Northampton and 5 State of Pennsylvania, have invented new and useful Improvements in Signals, of which the following is a specification.

This invention relates to a signal for motor vehicles, the general object of the invention being to provide a hand operated device which normally occupies a vertical position but when moved to a horizontal position will indicate that the vehicle is to make a turn or is to be stopped.

10 This invention also consists in certain other features of construction and in the combination and arrangement of the several parts, to be hereinafter fully described, illustrated in the accompanying drawings and 15 pointed out in the appended claims.

In describing my invention in detail, reference will be had to the accompanying drawings wherein like characters denote like or corresponding parts throughout the 20 several views, and in which:

Figure 1 is a view showing the invention in use on a closed type of vehicle.

Figure 2 is an elevation of the device.

Figure 3 is a sectional view thereof.

30 Figure 4 is a view similar to Figure 3 but showing the arm in lowered position.

Figure 5 is an enlarged sectional view showing the toggle link arrangement.

Figure 6 is a section on line 6—6 of Figure 5.

Figure 7 is a view of the link for connecting the handle to the toggle links.

Figure 8 is a view of the upper clip.

Figure 9 is a view of the lower clip.

40 Figure 10 is a view of the inner part of the handle.

Figure 11 is a sectional view through the outer end of the signal arm and the lamp casing.

45 In these views 1 indicates a cylinder which is attached to any suitable part of a vehicle, such as shown at A, by the brackets 2. A dome 3 is attached to the upper part of the cylinder and the lower part is closed by a base 4. A rod 5 passes through the dome into the cylinder and clips 6 and 7 are attached to said rod by set screws or the like. The clip 6 slides in a hole 8 formed in the base of the dome and has a slot 9 therein which receives an end of an arm 10 which carries at its outer end the lamp casing 11.

The arm is pivoted in the slot by means of a pin 12 and the slot is so formed that the arm can assume a horizontal position or a vertical position. Two sets of toggle links 13 pivotally connect the clip 7 with ears 14 on the base of the dome so that when these links are moved to open or closed position the rod 5 will be moved vertically and as the clip 6 is fastened to the rod, said clip will move with the rod and as it moves downwardly the arm 10 will be tilted upwardly, as its rounded end passes into the opening 8 so that said arm will be brought to a vertical position when the clip and rod reach 70 the limit of the downward position. When the toggle links are opened up the clip 6 will move upwardly and then the arm 10 will drop to a horizontal position.

In order to adjust the toggle links a rod 15 has its forked end 16 pivoted to the links and its other end connected with a hand lever 17 which is pivoted to a bracket 18 arranged within the body of the vehicle. The connection of the rod 15 with the lever is such that when the lever is in its upper position the links will be broken and thus the arm will be in raised position, as shown in Figures 2 and 3. When the lever is in its lowest position the links will be in extended position and then the arm will be in horizontal position, as shown in Figure 4.

50 In order to absorb the shock of the falling arm and to help raise the arm, I provide a spring 19 in the cylinder which engages a disk 20 on the end of the rod 5 and has its upper end bearing against a plate 21 in the cylinder. As the arm drops the spring will be compressed so that when the arm is moved upwardly the spring will tend to help lift 95 the arm to its vertical position.

A lamp 22 is arranged in the casing 11 and one of the conductors 23 of said lamp leads to a suitable source of supply, while the outer conductor is attached to a spring 100 contact 25 which is carried by but insulated from the bracket 18. When the hand lever 17 is swung downwardly it will contact with this spring contact 25 and thus ground the conductor 24 so that current will pass to 105 the lamp when the signal is in operated position.

I also attach a contact 26 to the horn of the vehicle or to another signal and provide a spring contact 27 on the hand lever 17 110 for wiping over the contact 26 as the lever is lowered, so that the horn will be sounded

just before the signal is given. By holding the hand lever in horizontal position and the contacts 27 and 26 in engagement with each other, the horn or other alarm will continue 5 to sound.

The arm 10 is guided in its movement by means of a slot 28 formed in the dome 3 and the movable parts are enclosed by said dome, the rod 15 passing through a hole 29 made 10 in the dome. I also prefer to form the dome in two parts so that access can be had to the interior thereof. I also prefer to make the casing 11 with transparent members in both faces so that the signal light can be seen 15 from the front as well as the rear.

From the foregoing it will be seen that I have provided a simple device for giving signals from a closed vehicle as well as an open one, it simply being necessary to swing 20 downwardly the hand lever 17 in order to throw the signal arm 10 into horizontal position to indicate that the vehicle is to be turned or stopped. After the turn has been made the lever 17 is swung upwardly to lift 25 the signal arm to vertical position. As the lever 17 is moved downwardly the horn is blown and then the circuit completed to the lamp 22.

It is thought from the foregoing description that the advantages and novel features 30 of my invention will be readily apparent.

I desire it to be understood that I may make changes in the construction and in the combination and arrangement of the several 35 parts, provided that such changes fall within the scope of the appended claims.

Having thus described the invention, what is claimed as new, is:—

1. A signal for a motor vehicle comprising 40 a casing, a vertically movable rod therein, a bracket attached to the rod, a signal arm attached to the bracket, the upper part of the casing having a vertical slot through which the arm extends, a horizontal 45 part in the casing having a hole therein through which the bracket moves, said horizontal part holding the arm in horizontal position when the bracket is in raised position and acting to move the arm into 50 vertical position when the bracket is being lowered and a hand operated member for moving the rod.

2. A signal for a motor vehicle comprising 55 a casing having a dome shaped upper end

with the base for the dome having an opening 55 therein, a rod vertically movable in the casing, a bracket on the rod movable in the opening, said dome having a slot therein, a signal arm pivoted to the bracket and guided 60 in its swinging movement upon the movement of the bracket by the slot and manually operated means for moving the rod.

3. A signal for a motor vehicle comprising 65 a casing having a dome shaped upper end with the base for the dome having an opening therein, a rod vertically movable in the casing, a bracket on the rod movable in the opening, said dome having a slot therein, a signal arm pivoted to the bracket and guided 70 in its swinging movement upon the movement of the bracket by the slot, manually operated means for moving the rod, such means comprising a hand lever, toggle links connecting a part on the rod with the part on the base of the dome and a link connecting 75 the hand lever with the toggle links.

4. A signal for a motor vehicle comprising 80 a casing having a dome shaped upper end with the base for the dome having an opening therein, a rod vertically movable in the casing, a bracket on the rod movable in the opening, said dome having a slot therein, a signal arm pivoted to the bracket and guided 85 in its swinging movement upon the movement of the bracket by the slot and manually operated means for moving the rod, and a spring for facilitating the downward movement of the rod and for cushioning the upward movement thereof.

5. A signal for a motor vehicle comprising 90 a casing having a dome shaped upper end with an opening in the base of the dome, a vertically movable rod in the casing, a bracket on the rod and movable in the opening, said bracket having a slot therein and 95 the dome having a slot therein, a signal arm having its inner end pivoted in the slot in the bracket and the arm being guided by the slot in the dome, a clip fastened to the rod, toggle links connecting the clip with a part 100 of the base, a hand lever, a link connecting the same with the toggle links, spring means in the casing and connected with the rod for cushioning the downward movement of the signal arm.

In testimony whereof I affix my signature.

WARREN S. SMITH.
